(57) **CLAIM**

The ornamental design for a zipper tooth, as shown and described.

DESCRIPTION

FIG. 1 is a perspective view for a tooth of a zipper, FIG. 2 is a front elevational view thereof, the rear being a mirror image,

FIG. 3 is a side elevational view thereof, the other side being a mirror image,

FIG. 4 is a top plan view thereof; and,

FIG. 5 is a bottom plan view thereof.

The broken lines shown throughout the drawings are for illustrative purposes only and form no part of the claimed design.
